UNITED STATES PATENT OFFICE.

LOUIS BESSIÈRE, OF PARIS, FRANCE.

DESIGN FOR A DRINKING-GLASS.

No. 39,047.

Specification for Design.

Patented Jan. 28, 1908.

Application filed December 11, 1907. Serial No. 406,109. Term of patent 7 years.

To all whom it may concern:

Be it known that I, LOUIS BESSIÈRE, a citizen of the Republic of France, residing at Paris, France, have invented a new, original, and ornamental Design for Drinking-Glasses, of which the following is a specification, reference being had to the accompanying drawing, forming part thereof.

The figure is a side view of a drinking glass, showing my new design.

I claim:

The ornamental design for a drinking glass, as shown.

LOUIS BESSIÈRE.
